UNITED STATES PATENT OFFICE.

DAVID M. COHN, OF EVANSVILLE, INDIANA.

BELT-BUCKLE.

1,227,998.

Specification of Letters Patent. Patented May 29, 1917.

Application filed May 29, 1916. Serial No. 100,545.

To all whom it may concern:

Be it known that I, DAVID M. COHN, a citizen of the United States, residing at Evansville, county of Vanderburg, and 5 State of Indiana, have invented certain new and useful Improvements in Belt-Buckles, of which the following is a specification.

This invention relates to belt buckles.

Wearers of men's belts encounter a tendency of the belt buckle and front portion of the belt to rise and override the upper edge of the trousers, thus detracting from a neat appearance. Cloth loops have been provided on the front of the trousers waistband to hold the belt down at this point, but the dressy appearance of the buckle is thereby marred.

The object of my invention is the provision, on a belt buckle having a front plate 20 which is designed to overlie the adjustable belt end, and a cam gripping bail or loop adapted to clamp the said belt end, of a finger or hook carried by said bail or loop which will be adapted to engage the garment to obviate the above-mentioned tendency and to improve the dressy appearance of the buckle and belt.

Certain modifications of the invention are hereinafter described and set forth in the 30 accompanying drawings to illustrate that it may assume different forms, but as the invention is susceptible of other embodiments in other forms, the disclosure is to be considered as illustrative, rather than restrictive, of the scope of the invention.

In the accompanying drawings:

Figures 1 and 2 are rear perspective views showing two different forms of the invention.

Referring first to Fig. 1, the buckle plate 40 or body 1 has rear flanges 2 in which is journaled at 3 the loop 4 having cam or wedge bar 5. One end of the belt is made fast to the loop 4 and the other, or loose, end is entered between the flanges 2 and 45 clamped against the rear face of body 1 by the cam or wedge bar 5.

In Fig. 1, the hinged loop 4 having cam 5 is located substantially centrally of the body 1 and carries the fixed hook or finger 50 11 and is adapted for use where a vertical cloth loop is on the outer part of the trousers waistband at the front thereof, the hook 11 engaging such cloth loop.

In the form shown in Fig. 2, the hook 12, 55 corresponding to hook 11, is disposed nearer the open loop 4.

In the forms of Figs. 1 and 2, the loop, cam, and hook are made as a single, integral stamping, rendering them inexpensive to 60 produce but the invention is not thus limited nor to the general central location of the hinges 3, as modifications of these features may be resorted to.

Having thus described my invention, 65 what I claim as new and desire to secure by Letters Patent, is:—

A belt buckle having a front plate designed to overlie the adjustable belt end, a cam loop hinged to said front plate adapted for attachment to the fixed belt end and for clamping the adjustable belt end, and a 70 fixed hook carried by the cam loop.

In testimony whereof, I hereunto affix my signature.

DAVID M. COHN.
